LOOSE LEAF BINDER

James C. Dawson, Webster Groves, Mo., assignor,
by mesne assignments, to Loose Leaf Metals
Company, a corporation of Missouri

Application December 24, 1934, Serial No. 758,901

1 Claim. (Cl. 129—24)

The invention relates to loose leaf binders of the toggle arch type. Its object is to provide a simple and inexpensive binder especially for note book service; and it consists in a structure such as hereinafter described, and as illustrated in the accompanying drawing, in which

Fig. 1 is a perspective view of the binder when open, some parts being broken away; and

Fig. 2 is a detail of an end portion of the metal.

10 The cover 10 of the binder is formed of a single uninterrupted sheet of flexible material, such as leather or the like.

15 The metal comprises a pair of rods 11, having their ends formed into sections of sheet-holding rings and being offset laterally, as at 12, 13, to form toggle joints 14, and a spring plate 15, having downturned margins 16 for clamping the body portions of the rods 11. The plate 15 is apertured, as shown at 17, to accommodate the up-
20 standing end portions 18 of the rods, which constitute the sheet-holding elements and mate together to form arches.

25 The length of the body portion of the plate 15 is slightly less than the width of the sheet 10. The central portion of the plate 15 is prolonged at each end beyond the body portion, and is bent downwardly to close the end of the body portion, as shown at 19,—this portion extending down-

wardly approximately to the line of the margins 16 of the plate and then bent forwardly, as a tongue 20, which is folded backwardly, as shown at 21, to inclose the margins of the cover 10.

30 The upper part of the downturned portion 19 of the plate slopes backwardly to permit the flexing of the body portion of the plate 15, while having the effect of somewhat stiffening that portion and thus permitting the use of lighter stock. The inner part 20 of the forwardly projecting tongue 10 is transversely concave, as shown, and the backwardly turned portion 21 is correspondingly bent.

35 The metal having been fitted to the cover by having the margins of the cover inserted between the parts 20 and 21, the latter are clinched together by pressure, and, if desired, may be indented by the use of a suitable tool to bite into the material of the cover.

I claim as my invention—

40 A loose leaf binder comprising a cover formed of an uninterrupted sheet of flexible material, a transversely arched spring plate, openable sheet-holding prongs in toggle engaged sets carried by the arched plate, such plate having its end portions extended beyond the arched portion 25 and offset downwardly and folded backwardly to detachably engage the cover.

JAMES C. DAWSON.
